J. VANDENBERG

BAG HANDLE ATTACHING DEVICE

Filed Sept. 18. 1922

INVENTOR:

Jacob Vandenberg
BY Allen Allen

ATTORNEYS.

UNITED STATES PATENT OFFICE.

JACOB VANDENBERG, OF WYOMING, OHIO, ASSIGNOR TO THE SECURITY BAG COMPANY, OF CINCINNATI, OHIO, A CORPORATION OF OHIO.

BAG-HANDLE-ATTACHING DEVICE.

Application filed September 18, 1922. Serial No. 588,877.

To all whom it may concern:

Be it known that I, JACOB VANDENBERG, a citizen of the United States, and residing in the town of Wyoming, county of Hamilton, and State of Ohio, have invented certain new and useful Improvements in Bag-Handle-Attaching Devices, of which the following is a full, clear, and exact description, reference being had to the accompanying drawings, forming a part of this specification.

My invention relates to mechanisms for use in the attaching of string handles to that type of paper bag, known as a "shopping bag."

In bags of this character I have evolved a method of attaching the string handle by means of gummed tape and a cemented bag fold, which is very strong, and simple, and will outlast the bag, so far as tearing strings are concerned.

My mechanism which forms the basis of this invention is directed to means for use in the attaching of the string handles according to my method.

The method includes briefly the insertion of the string through a pair of previously formed holes in the side of the bag, said string ends being thrust through from the outside of the bag and permitted to rest on the inner surface thereof. A fold of the open end of the bag is cemented down over the string where it passes through the holes, and a piece of gummed paper tape or its equivalent is pasted down over the ends of the string as they lie on the inner surface of the bag.

The mechanism has as its object the provision of a holder for the bag during this operation, a guide for the string, and a clamp for the gummed tape, which clamp has also a clearance for the string, thereby forcing the tape well down around the ridge formed by the string on the inside of the bag.

I accomplish these objects by that certain construction, an arrangement of parts to be hereinafter more specifically pointed out and claimed.

In the drawings,

Figure 1 is a perspective view of the machine, when not in use.

Figure 2 is a like view showing the machine in use, after the string has been inserted and the clamp swung down. 55

Figure 3 is a detail of a portion of a bag showing the method of attaching the handle.

Referring first to the bag, I have indicated at 1^a, a portion of one side of a bag, which has an inward fold 2^a around its upper edge 60 or mouth. Punched out of the body of the bag, on a line to be lapped by this fold are a pair of holes 3^a, 3^a, for the string handle.

I have shown but one side of the bag, but it will be understood that both sides will be 65 similarly formed.

The piece of stout cord or string 4^a, is bent into a half loop and its ends thrust through the holes 3^a from the outside of the bag. The fold is then cemented on several 70 lines adjacent the holes and wiped down over the string and the bag. The ends 5^a, of the string then lie on the face of the bag, and a piece of gummed tape 6^a is set over the ends, and preferably also, partially over the 75 fold, and wiped down in place. I have found that a handle so mounted cannot be grasped in the hand and wrenched off while holding the closed end of the bag, but that the material of the bag will give way instead. 80

Referring now to the invention involved in this application, I have shown a work table 1, on which is mounted a standard 2, carrying a swiveled sleeve 3. The sleeve is formed 85 with an arm 4, having a handle 5, and in the end of the arm is mounted a pressure roller.

This roller is shown at 6, and is mounted in the arm by means of a bifurcated 90 holder 7.

Mounted on the table is a bag holder or spreader shoe, formed of a board 8 having mounting arms 9, 9, which are pivoted or hinged in brackets 10, 10, at the front edge 95 of the table. One of the arms 9 extends forwardly as at 11, where it is connected to a lever 12, operated from a foot treadle. The treadle is shown at 13, hinged to a floor plate 14, and pulled by a spring 15 into position to force the shoe to lie flat on the table. A depression of the treadle by the foot will swing the shoe on its hinges to a slanting position above the table. 100

Mounted on the top of the shoe is a curved bag spreader tongue 16, and beneath the elevated end of the tongue is a heavy presser iron 17, hinged at 18 to the forward edge of the shoe.

It should be noted that the table is formed with grooves 19, 19, therein, which are set to register with the string handle ends, and the presser iron has also like spaced grooves

10 20, 20. The shoe at its forward edge has for a short distance, (a fraction of an inch) like grooves 21, 21.

As so constructed the device operates as follows: The operator takes a bag, presses 15 the foot treadle and slips the bag over the shoe, at the same time spreading it so as to clear the presser iron. He pulls the bag far enough over the shoe to bring the edge of the mouth thereof about to the edge of 20 the table, and permits the shoe to drop, thereby holding the bag tight, and in an open position.

He then takes a piece of string, cut for 25 a handle, and inserts the ends of the string in the grooves 19 and up through the holes 3^a, 3^a, in the bag, forcing the string to the position about as shown in Figure 3. In the preferred form of bag this involves a forcing out of the way of the top fold of 30 the bag and the operator next takes a glue brush and applies it to the top fold, adjacent the string pieces.

He next pulls a piece of gummed tape 35 from a moistening tape holder, and lays it down across the bag, so as to cover the string ends, from the fold to approximately the tips of the said ends.

Next he swings down the presser iron, 40 reaching into the bag with his hand to do so, and swings the arm 4 over the shoe, with the result that the roller presses down on the shoe.

The result of the grooves in the table, and 45 the guiding function of the round holes in the bag, is to force the string to lie in the table grooves, and since the grooves terminate in the shoe, within a fraction of an inch of its forward edge, this holds the string also, and serves as a guide as to the 50 extent to which the string ends should be forced into the bag. The grooves in the presser iron register with the table grooves, and thus the result of pressing down on the iron is to wipe the tape and the material of 55 the bag closely around the string ends, thereby completely housing the string between the bag and the tape, and providing a permanent string end retaining means.

The entire operation can be done very 60 quickly with the mechanism now described, and when finished, the shoe is elevated, the bag drawn off, and then reversed and the other side treated in a like manner. In practice it is found to be better to attach 65 handles to one side of a batch of bags, and

then turn over the entire batch and attach handles to the other side, but this is naturally non-essential.

I wish to note that the mechanism described is the one preferred by me in use, 70 but that modifications may be made therefrom, while still preserving the essential features thereof, which I set forth in the appended claims.

Having thus described my invention, 75 what I claim as new and desire to secure by Letters Patent, is:

1. In a device of the character described, a table having interspaced grooves to register with the ends of a string handle, a 80 bag expanding shoe mounted on the table and adapted to hold a bag with interspaced holes in said bag in registry with said grooves, and a presser device adapted to apply pressure against the inner surface of 85 the bag.

2. In a device of the character described, a table having interspaced grooves to register with the ends of a string handle, a bag 90 expanding shoe mounted on the table and adapted to hold a bag with interspaced holes in said bag in registry with said grooves, and a presser device adapted to apply pressure against the inner surface of the bag, 95 said presser device also having grooves therein to register with the grooves in the table.

3. In a device of the character described, a table having interspaced grooves to register with the ends of a string handle, a bag 100 expanding shoe mounted on the table and adapted to hold a bag with interspaced holes in said bag in registry with said grooves, and a presser device adapted to apply pressure against the inner surface of the bag, 105 said presser device comprising a hinged presser foot mounted on the shoe, and adapted to swing down over the table, and movable means mounted in connection with the table and adapted to exert pressure 110 against the foot.

4. In a device of the character described, a table having a bag retaining and expanding shoe hingedly connected with said table, and adapted to swing to position with its 115 end elevated away from the table for pulling on a bag, and to position in contact with the table to hold a bag thereagainst, and a presser foot mounted in connection with the above named parts and adapted to swing 120 down against the inside of a bag when mounted over the shoe and held thereby against the table.

5. In a device of the character described, a table having a bag retaining and expanding shoe hingedly connected with said table, and adapted to swing to position with its end elevated away from the table, for pulling 125 on a bag, and to position in contact with the table to hold a bag thereagainst, and a 130

presser foot mounted in connection with the above named parts and adapted to swing down against the inside of a bag when mounted over the shoe and held thereby 5 against the table, said table and foot having registering grooves therein to permit a wiping in action about the string.

6. In a device of the character described, a table having interspaced grooves to register with the ends of a string handle, a 10 bag expanding shoe mounted on the table and adapted to hold a bag with interspaced holes in said bag in registry with said grooves, and a presser device adapted to apply pressure against the inner surface of the 15 bag, said presser device comprising a hinged presser foot mounted on the shoe, and adapted to swing down over the table, and movable means mounted in connection with 20 the table and adapted to exert pressure against the foot, said movable means comprising a swiveled sleeve, and a pressure roller carried by said sleeve and moving in a path to make a pressure connection with the 25 shoe when same is swung down against the table.

7. In a device of the character described, the combination with a table, of a bag expanding and retaining device comprising a shoe, adapted to rest against the table, 30 arms on the shoe and hinged in connection with the table, means for swinging the shoe into a position elevated above the table on said arms, and angled with relation to the table, and said shoe being so formed as to 35 expand the bag at its end toward the working end of the table.

8. In a device of the character described, the combination with a table of a bag expanding and retaining device comprising a 40 shoe, adapted to rest against the table, arms on the shoe and hinged in connection with the table, means for swinging the shoe to a position elevated above the table on said 45 arms and angled with relation to the table, an upwardly curved, forwardly extending tongue on the shoe, and a presser foot hinged to the shoe and protected by means of the tongue, as and for the purpose described.

JACOB VANDENBERG.
